UNITED STATES PATENT OFFICE.

FRANK M. ULMER, OF PHILADELPHIA, PENNSYLVANIA.

LOCK-FAUCET.

1,026,725.

Specification of Letters Patent

Patented May 21, 1912.

Application filed January 12, 1911. Serial No. 602,202.

To all whom it may concern:

Be it known that I, FRANK M. ULMER, of Philadelphia, in the county of Philadelphia and State of Pennsylvania, have invented 5 certain new and useful Improvements in Lock-Faucets, whereof the following is a specification, reference being had to the accompanying drawings.

My invention relates to a lock faucet in 10 which the spigot can be opened only after unlocking the same with a key and turning the handle in opposition to continuous spring pressure, which, upon releasing the handle, instantly closes and re-locks the 15 spigot.

In the accompanying drawings, Figure I, is a longitudinal sectional view of a faucet embodying my invention, the spigot being open. Fig. II, is a similar sectional view 20 of the same, the spigot being closed. Fig. III, is a horizontal sectional view along the line III, III, of Fig. I. Fig. IV, is a similar view along the line IV, IV, of Fig. II.

The faucet 1, is provided with a tapering 25 plug or spigot 2, traversed by the port 3. The lower end of the plug is held in place by the washer 4, and around its upper edge is a ring of packing 5. The faucet is sur- 30 mounted by a collar 6, within which is mounted the enlarged stem 7, suitably at- 35 tached to the plug 2, as by a double screw 8. The upper end of this stem carries the handle 9. Between the stem 7, and the collar 6, a space 12, is provided within which a coiled 40 spring 13, is seated, the ends being attached respectively to the collar and to the stem, so that the spring exerts continuous ten- 45 sion to draw the stem and plug around to the position in which the faucet is closed. The revolution of the stem within its collar, and therefore the rotation of the plug of 50 the faucet, is confined to a quadrant by means of the engagement of a lug 15, with the edges of a quadrant sector 16, cut in the upper edge of the collar 6.

Within the stem 7, is suitably seated a bolt 55 20, constantly spring pressed in a direction radial to the stem by the spring 21. Within the plane of the rotation of the bolt, the

collar 6, is provided with a bolt hole 22, 50 into which the bolt slips, under tension of the spring, when the two are in registry. This registry occurs when the plug 3, is turned so that its port is at right angles to the faucet and the same closed. The bolt 55 can only be withdrawn so as to turn the plug and open the faucet by means of locking mechanism as follows:—Seated vertically within the upper part of the stem 7, is the cylindrical barrel 25, of a lock capable of 60 being rotated by insertion and manipulation of the key 26. The lock is a spring lock normally rotating the barrel to position of closure, except as turned by the key. The lower end of the barrel is provided with a 65 pin 28, received within a quadrant slot 29, in the base of the stem. The upper edge of the bolt 20, is furnished with a cam surface 30, so related to the end of the pin 28, that the movement of the latter as the barrel of the lock is rotated, operating upon its cam surface withdraws the bolt from the bolt hole.

In operation the faucet is normally closed with the handle and port at right angles 75 to its axis and in this position is locked by the shooting of the bolt into the bolt hole. To open the faucet, the key 26, must be inserted and the barrel of the lock rotated suf- 80 ficiently to withdraw the bolt, whereupon by turning the handle 9, to a position par- 85 allel to the axis of the faucet, the latter is opened. This turning movement is opposed by the coiled spring 13, so that the moment the handle is released, it returns to the po- 90 sition of Fig. II, and unless pressure on the key 26, prevents it, the bolt is shot into the bolt hole, and the faucet is locked again in its closed position.

The faucet thus described is useful to 90 prevent waste or improper drawing of liquids, as well as to confine the use of the faucet to those provided with a key.

Having thus described my invention, I claim:—

The combination in a faucet with its plug, a spring by the continuous tension of which the plug is normally rotated to close the

faucet; a spring-pressed bolt by which the plug is normally locked in its closed position; and a key-operated lock by rotation of which the bolt is withdrawn from its 5 bolt hole to permit rotation of the plug to open the faucet.

In testimony whereof, I have hereunto

signed my name at Philadelphia, Pennsylvania, this eleventh day of January, 1911.

FRANK M. ULMER.
